UNITED STATES PATENT OFFICE.

REINHOLD MENSCHEL, OF BERLIN, GERMANY.

SWIMMING AND RUNNING SHOE.

Application filed January 6, 1927, Serial No. 159,476, and in Germany December 9, 1926.

This invention relates to a shoe or sandal-like structure suited particularly for swimming and running. The gist of the invention resides therein that a base-member, the specific weight of which is lower than that of water, is combined with a frame consisting preferably of aluminium and serving as support for the foot and being provided with means for fastening it to the same; besides, stays extending laterally from said frame hold a web and are so arranged at, and hinged to, the said frame that they are moved from their normal position in which they are located practically parallel to each other outwardly to all sides by the resistance which the water presents to said web when the foot is pushed rearwardly as done in swimming.

If the shoe is used for walking, the stays hang down and remain out of action. If the shoe is used, however, for swimming, the stays spread outwardly, as already stated, and act now like the webs of aquatic birds or water fowl. When the feet are drawn towards the body, the web gives way, and in the reverse direction it is extended or spread by the spreading stays, as already mentioned.

The invention is illustrated diagrammatically and by way of example on the accompanying drawing on which Figure 1 is a plan of a shoe designed according to this invention and having its stays with the web spread out; Figure 2 is a side-view of the same shoe, the stays and the web hanging, however, downwards; Figure 3 is a vertical cross section in the plane A—B of Fig. 2, seen from the right to the left, the web being omitted in this figure; Figure 4 shows a portion of the frame with some of the stays, this figure being drawn to an enlarged scale; and Figure 5 is a section in the plane C—D of Fig. 4.

On the drawing, *n* denotes a plate, preferably of aluminium, and *b* is an upwardly bent flange of this plate. The plate *n* serves as support for the foot; it may have a bulged-out portion *q* located below the instep of the foot and serving as a separate support just for this portion of the same. To the upper side of the plate *n* is attached a sandal-like structure *a* which may consist of linen or rubber, and may be affixed to the foot by straps and clasps or the like.

Below the plate *n* are base members *d* consisting either of natural or artificial cork

enclosed in sail-cloth or the like, or of hollow rubber that can be inflated with air by means of a pump. This latter constructional form is that illustrated. The hollow rubber bodies *d* are provided with a valve *h* resembling that of a bicycle tire, and from this valve extends an air-tube *m* into the said bodies. The lowermost member of the entire structure consists of a plate of rubber or leather *r*, is attached to the bottom surface of the rubber body *d* and serves as a sole for the whole.

e denotes the stays which are attached, or hinged, to the plate *n* in a manner as follows: From the flange *b* of the plate *n* extend upwardly metal strips *p*, each of which has at its upper end two parallel lugs *g*. The strips *p* and the flange *b* may be connected with each other by rivets or the like. Each pair of lugs *g* carries a pin *h* from which is suspended a stay *e*. A web *c* extends around the plate *n* and is attached to the inner sides of the stays *e*, as shown in Fig. 1, but instead of letting the web consist of only one layer, as in the constructional form shown, it may be composed of two layers, one being located at the lower side, the other at the upper side of the stays, and both being connected with each other in any suitable manner. The web may consist of rubber, silk, fish-skin, or the like; its upper or inner rim is attached to the outer surface of the flange *b*, and the portion *s* located between the flange and the stays is so broad that it forms folds when the web is not extended, the folded portion being expanded when the web is stretched.

If the shoe is employed on the land, it looks as in Figs. 2 and 3, in which case the stays hang freely down. If it is used, however, in the water for swimming, the web is spread together with the stays when the foot is pushed rearwards, and is collapsed when the foot is drawn towards the body. Figures 2 and 3 show this position, and Figure 1 shows the other one. In this other position the outward movement of the stays is limited by their upper ends contacting with the upper edges of the strips *p*.

There are, in the constructional form shown as an example, two superposed bodies *d* made integral with each other. In other words: One body is subdivided by a horizontal partition wall into two superposed chambers *d*. It is a matter of course, that there may be more than one partition wall,

or more than two chambers, so that the body is inflated practically only vertically. When the shoes of this kind are to be transported, the bodies *d* may be compressed, the valve *h* being opened prior thereto, so that the bulk of the shoes can be correspondingly reduced.

The device is very suited for persons desiring to learn to swim, as well as for persons desiring to swim a long time, or to cover a long way in the water.

I claim:

1. A swimming and running shoe, comprising, in combination, a foot support, the specific weight of which is lower than that of water, a frame attached to the upper side of said support, means for attaching said frame to a foot, stays hinged to the said frame, and a web fastened to said stays, and means for limiting the outward movement of the stays with said web when these members have arrived in their proper operative position, substantially as set forth.

2. A swimming and running shoe, comprising, in combination, a foot support, the specific weight of which is lower than that of water, an aluminium frame attached to the upper side of said support, means for attaching said frame to a foot, stays hinged to the said frame, and a web fastened to said stays, and means for limiting the outward movement of the stays with said web when these members have arrived in their proper operative position, substantially as set forth.

3. A swimming and running shoe, comprising, in combination, a foot support formed by an air-filled chamber or air-filled chambers, a frame attached to the upper side of said support, means for attaching said frame to a foot, stays hinged to the said frame, and a web fastened to said stays, and means for limiting the outward movement of the stays with said web when these members have arrived in their proper operative position, substantially as set forth.

4. A swimming and running shoe, comprising, in combination, a foot support consisting of an air-filled rubber body, a frame attached to the upper side of said support, means for attaching said frame to a foot, stays hinged to the said frame, and a web fastened to said stays, and means for limiting the outward movement of the stays with said web when these members have arrived in their proper operative position, substantially as set forth.

5. A swimming and running shoe, com-

prising, in combination, a foot support, the specific weight of which is lower than that of water, a walking sole secured to the bottom side of said support, a frame attached to the top side of the said support, means for attaching said frame to a foot, stays hinged to the said frame, and a web fastened to said stays, and means for limiting the outward movement of the stays with said web when these members have arrived in their proper operative position, substantially as set forth.

6. A swimming and running shoe, comprising, in combination, a foot support, the specific weight of which is lower than that of water, a frame attached to the upper side of said support, means for attaching said frame to a foot, stays hinged to the said frame, and a web fastened to said stays and having its inner rim affixed to the rim of the said frame, the web portion located near this rim being folded when in its position of rest and expanded when in its operative position, and means for limiting the outward movement of the stays with said web when these members have arrived in their proper operative position, substantially as set forth.

7. A swimming and running shoe, comprising, in combination, a foot support, the specific weight of which is lower than that of water, a frame attached to the upper side of said support, means for attaching said frame to a foot, metal strips extending upwardly from the said frame, outwardly bent pairs of lugs at the free ends of said strips, pins carried by said pairs of lugs, stays hinged to said pins, and means for limiting the outward movement of the stays with said web when these members have arrived in their proper operative position, substantially as set forth.

8. A swimming and running shoe, comprising, in combination, a foot support consisting of a hollow rubber body, an air-valve connected with this body, a frame attached to the upper side of said support, means for attaching said frame to a foot, stays hinged to the said frame, and a web fastened to said stays, and means for limiting the outward movement of the stays with said web when these members have arrived in their proper operative position, substantially as set forth.

In testimony whereof I affix my signature.

REINHOLD MENSCHEL.
